UNITED STATES PATENT OFFICE.

CHARLES McCARTER, OF DECATUR, ILLINOIS.

PIPE AND NUT WRENCH.

1,374,748.

Specification of Letters Patent. Patented Apr. 12, 1921.

Application filed January 6, 1920. Serial No. 349,727.

To all whom it may concern:

Be it known that I, CHARLES McCARTER, a citizen of the United States, and a resident of Decatur, in the county of Macon and State of Illinois, have invented a new and useful Pipe and Nut Wrench, of which the following is a full, clear, and exact description.

This invention relates to wrenches and particularly to an improved nut and pipe wrench which has for an object to provide an improved quick setting feature whereby the parts may be quickly and easily set to the desired size.

Another object of the invention is to provide a wrench in which a quick setting feature is embodied and also means for locking the movable jaw in any set position.

In the accompanying drawing:

Figure 1 is a side view with certain parts broken away, illustrating an embodiment of the invention.

Fig. 2 is a view similar to Fig. 1 except that the sliding jaws are in an unlocked position.

Fig. 3 is a fragmentary sectional view through Fig. 1 on line 3—3.

Fig. 4 is an end view of a pair of locking wedges embodying certain features of the invention.

Referring to the accompanying drawing by numerals, 1 indicates a handle merging into a shank 2 which carries a stationary head 3 having a nut jaw 4 and a pipe jaw 5. If desired the pipe jaw 5 could be made of some other shape, as for instance at the opposite angle to the jaw 6 so as to produce an alligator effect. The jaw 6 is arranged on the sliding sleeve 7 which sleeve also carries a movable jaw 8 coacting with jaw 4 while jaw 6 coacts with jaw 5. The sleeve 7 may be made in any suitable manner, but it has been found convenient to make the same in two parts as shown in Fig. 3 and connect the parts together by suitable bolts or rivets 9, whereby the jaw 6 is solid and is integral with the remaining part of the sleeve 7, while the jaw 8 is also integral with sleeve 7. It is, of course, understood that removable faces could be provided for any of the jaws without departing from the spirit of the invention. Sleeve 7 adjacent the side of the shank 2 carrying the teeth 10 is provided with a hollowed out portion or chamber 11 in which a locking cam 12 and a shifting cam 13 are positioned. The lock-

ing cam 12 slides freely between the shoulders 14 and 15, said cam being interlocked with the cam 13 as shown in Fig. 4, wherein it will be seen that tongues 16 and 17 are provided for the cams and corresponding grooves. The cam 13 is normally urged to the position shown in Fig. 1 by a spring 18 having a suitable seat at 19 in the cam 13 and a seat 20 in the sleeve 7. The sleeve 7 is provided with an opening or passage-way 21 in which the neck 22 of the cam 13 is positioned and in which it freely slides back and forth, said neck merging into a knob or pull 23 which is easily grasped by the operator for pulling the cam 13 from the position shown in Fig. 1 to that shown in Fig. 2. As the cam 13 is moved rearwardly, or in a direction way from the jaw 6, the cam action of the tongues 16 and 17 will cause the cam 12 to move away from the shank 2 so that teeth 24 on the cam 12 will become disengaged from the teeth 10 on shank 2.

As shown in Fig. 3 the neck 22 and the knob 23 are both hollowed out for receiving a pivotally mounted latch 25, held in position by a suitable pivotal pin 26 and provided with a thumb member 27 and with a locking pin or extension 28 designed to fit into the respective recesses 29 and 30 under different circumstances. The under side of the thumb member 27 is engaged by a spring 31, which spring is also seated in a depression 32 in knob 23 in order to resiliently urge the catch to the position shown in Fig. 3. When the parts are in the position shown in Fig. 1, and it is desired to shift the movable jaws 6 and 8, the thumb member 27 is depressed against the action of spring 31 which will cause the pin or projection 28 to move out of the socket 29. When this has been done the knob or pull 23 may be moved to the rear so that the parts will assume the position shown in Fig. 2, after which the thumb member 27 is released. Upon releasing the thumb member the pin or projection 28 will automatically move into the socket 30 and thereby lock the cam 12 in its disengaged position, thus permitting the sleeve 7 to freely slide back and forth. By the use of the sockets 29 and 30 and the pin or projection 28, the cam 12 may be locked in an engaged position or in a disengaged position, which is of importance as it permits a quick adjustment of the sleeve at one time and at another causes

the sleeve to be locked in a set position so as to always fit a nut or other article being operated upon.

What I claim is:

- 5 A wrench of the character described comprising a shank, a stationary jaw arranged on the shank, a sleeve slidingly mounted on said shank formed with a jaw co-acting with the stationary jaw, said sleeve being 20 formed hollow and with an opening facing the shank and an opening in the end arranged parallel with said shank but spaced therefrom, a cam arranged in said sleeve formed with a surface for engaging the 25 shank, and an inclined surface on the opposite side, a shifting cam having a beveled surface engaging said inclined surface, said shifting cam having a hand-hold projecting through the second mentioned opening in said sleeve, said sleeve being provided with a plurality of notches, a pivotally mounted catch arranged in said hand-hold provided with a thumb member and with a projection adapted to fit into one of said notches for locking the shifting cam in any desired position.

CHARLES McCARTER.
